MIXING SLAB

Seward C. Hoel, Milnor, N. Dak.

Application August 11, 1943, Serial No. 498,241

5 Claims. (Cl. 107—46)

The present invention relates to new and useful improvements in mixing slabs particularly for the prescription departments of drug stores, and has for its primary object to provide, in a manner as hereinafter set forth, a device of this character wherein the mixing surface may be expeditiously and conveniently renewed after each use of the device.

Another very important object of the invention is to provide a mixing slab of the aforementioned character comprising novel means for firmly securing the renewable mixing surface in position.

Other objects of the invention are to provide a mixing slab of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts through the several views, and wherein:

Figure 1 is a top plan view of a mixing slab constructed in accordance with the present invention.

Figure 2 is a view in side elevation of the device.

Figure 3 is a top plan view with parts omitted.

Figure 4 is a view in longitudinal section, taken substantially on the line 4—4 of Figure 1.

Figure 5 is a cross-sectional view, taken substantially on the line 5—5 of Figure 2.

Referring now to the drawings in detail, it will be seen that the embodiment of the invention, which has been illustrated, comprises a frame of suitable material which is designated generally by reference numeral 1, this frame being substantially rectangular in plan.

The frame 1 includes side and end members 2 and 3, respectively, the former having formed in one end portion angular slots 4 in which a roll of parchment paper 5 is rotatably mounted.

Journalized between the other end portions of the side members 2 is a roller 6 beneath which the parchment 5 passes. The adjacent end member 3 of the frame 1 has formed therein a slot 7 through which the parchment is drawn after passing under the roller 6. A bar 8 on the frame 1 parallels the slot 7 and provides a tear-off edge for the parchment.

Mounted on the side members 2, between the end members 3, is a panel 9. A spring 10 beneath

the panel 9 is engaged with the roll 5 for frictionally securing said roll against idle rotation.

Mounted on the panel 9 is a pair of transversely elongated plates 11 which are spaced from the end members 3. Transverse locking bars 12 are slidably mounted on the panel 9 between the plates 11 and end members 3. The bars 12 have fixed therein rods 13 which are slidably engaged in bores provided therefor in the plates 11.

Coil springs 14 on the rods 13 between the plates 11 and the bars 12 yieldingly urge said bars toward the end members 3. Projecting from the outer edges of the bars 12 are blades 15, said blades being engageable in grooves 16 which are provided therefor in the opposed edges of the end members 3 for firmly securing the parchment 5 in position.

A crankshaft 17 is journaled transversely on the frame 1 between the plates 11. Bars 18 connect the bars 12 to the throws 19 of the crankshaft 17 for retraction thereby against the tension of the coil springs 14. The end portions of the crankshaft 17 are formed to provide operating handles 20. Grooves or channels 21 in the upper faces of the plates 11 accommodate the connecting bars 18.

Mounted on the plates 11 and extending over the slideable bars 12 is a slab 22 of suitable material. The bars 12 are slideable beneath the end portions of the slab 22. This is illustrated to advantage in Figure 4 of the drawings.

It is thought that the operation of the device will be readily apparent from a consideration of the foregoing. Briefly, the roll of parchment paper 5 is mounted for rotation in the closed ends of the angular slots 4. The strip or web constituting the renewable mixing surface of the device is then threaded upwardly between the adjacent bars 12 and end member 3. Of course, the crankshaft 17 is first turned to retract the bars 12. The parchment paper is carried forwardly across the slab 22 and inserted downwardly between the other bar 12 and the adjacent end member 3. The paper passes beneath the roller 6 and emerges from the frame 1 through the slot 7. The crankshaft 17 is then turned to permit the coil springs 14 to project the bars 12 to operative or locking position, thus firmly securing the paper 5 in position on the slab 22. The device is now ready for use. After the device has been used and when a new mixing surface is desired, the shaft 17 is turned to again retract the bars 12 against the tension of the springs 14, thus releasing the paper. The paper is then pulled forwardly through the slot 7 until

the used portion has been withdrawn and a new surface is in position on the slab 22. The used portion is then torn off on the blade or strip 8 and the bars 12 are again released to locking position. The device is now ready to be used again. The spring 10 frictionally keeps the paper taut while a new surface is being drawn into position.

It is believed that the many advantages of a mixing slab constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A mixing slab of the character described comprising a frame, a web supporting slab mounted on said frame, securing means beneath each end portion of the slab said securing means being cooperable with the frame for releasably securing a web in position on said slab, and manually operable means for simultaneously releasing said securing means.

2. A mixing slab of the character described comprising a frame, including end members, a web supporting slab mounted on said frame, and means on the frame beneath the end portions of the slab and cooperable with the end members for releasably securing a web in position on the slab.

3. A mixing slab of the character described comprising a frame including end members, a web supporting slab mounted on the frame, bars slidable on the frame beneath the slab and cooperable with the end members for releasably securing a web in position on said slab, and means for actuating the bars to operative and inoperative position.

4. A mixing slab comprising a frame, a panel mounted on the frame, plates mounted on the panel, a web supporting slab mounted on said plates, bars slidable between the slab and the panel and cooperable with the frame for releasably securing a web in position on said slab, a manually operable crankshaft rotatably mounted on the frame between the plates, and means operatively connecting the bars to said crankshaft for retraction thereby.

5. A mixing slab of the character described comprising a frame including side and end members, a panel mounted on the side members, a pair of spaced plates mounted on said panel, a web supporting slab mounted on the plates, bars slidable between the slab and the panel and cooperable with the end members for releasably securing a web in position on said slab, pins on the bars slidably engaged in the plates, coil springs on the pins for urging the bars toward locking position, a crankshaft operable between the plates, and bars operatively connecting the first-named bars to the crankshaft for retraction thereby.

SEWARD C. HOEL.
